SUCTION PRODUCING APPARATUS FOR VACUUM CLEANERS

Jonathan P. Glasby, Jr., Verona, Lubin Palmer, Jr., Upper
Montclair, and Frank P. Pendleton, Montclair, N. J.,
assignors to J. P. Glasby Manufacturing Co., Inc., Belle-
ville, N. J., a corporation of New Jersey

Application March 26, 1956, Serial No. 40,771

Term of patent 14 years

(Cl. D9—2)

The single figure is a suction producing apparatus for vacuum cleaners, showing our new design.

The fragmentary portions shown in broken lines are for illustrative purposes only.

We claim:

The ornamental design for a suction producing apparatus for vacuum cleaners, as shown and described.
